ATTORNEYS

UNITED STATES PATENT OFFICE.

JOHN H. J. HAINES, OF NEW YORK, N. Y.

PHONOGRAPHIC REPRODUCER.

1,310,946.

Specification of Letters Patent. Patented July 22, 1919.

Application filed June 15, 1918. Serial No. 240,154.

To all whom it may concern:

Be it known that I, JOHN H. J. HAINES, a citizen of the United States, residing at the city of New York, in the borough of 5 Manhattan and State of New York, have invented certain new and useful Improvements in Phonographic Reproducers, of which the following is a full, clear and exact description.

10 This invention relates to phonographs and has special reference to that part of the machine known as the reproducer, the object of the invention being to provide a reproducer which will operate with equal efficiency in connection with records which have been made either by an "up and down" cut or by a "lateral cut of uniform depth" of the recording stylus.

It is well understood in the art that a 20 record groove formed by the so-called "lateral" cut, in actuating the stylus of the reproducer, swings the latter to the right and left, while the record groove which is made by the so-called "up and down" cut, swings 25 the stylus in a corresponding up and down direction. It has therefore been found difficult to provide a reproducer which will act with equal efficiency in connection with either style of cut on account of the fact 30 that the reproducer as a whole cannot be shifted in position with respect to the face of the record so that the vibration of the needle will have the same effect upon the diaphragm in each case. It is obviously an 35 advantage to have a reproducer which will operate in connection with either style of record for the reason that both styles are in common use and the expense involved in having two reproducers is, of course, to be 40 avoided, if possible. The primary object 45 of my invention is to provide a reproducer which can be used at will with records of either style of cut. A further object of the 50 invention is to combine in one instrumentality a reproducer and a sound amplifier.

My invention therefore comprises the attaching of a stylus to a diaphragm by means of a connecting member having a relation to the diaphragm such that by mounting it 55 in either of two angular positions the vi-

brations imparted to the needle by a lateral cut record will be conveyed to the diaphragm in the same manner and to the same extent as when the diaphragm is in its other position and operating in connection with 55 the up and down cut. My invention also comprises the mounting of the stylus rigidly upon a conical diaphragm of comparatively large diameter which being somewhat of the shape of a horn serves to amplify and 60 control the direction of the sound.

Referring to the accompanying drawing: Figure 1 represents in side elevation, with parts in section, the turn-table of a phonograph with my improved reproducer and 65 amplifier applied thereto in operative position;

Fig. 2 is a plan of the outside of the reproducer;

Fig. 3 is a fragmentary enlarged view at 70 the apex of the reproducer showing the stylus mounting; and

Fig. 4 is an enlarged detail of the means for mounting the reproducer upon the machine.

75

The reproducer consists essentially of a large cone 1 of sheet material, such as metal, leatheroid or other suitable stiff material, provided with a hoop 2 around its edge to give it definite form and stability and to 80 serve as a frame to facilitate the mounting of the cone in operative position upon the machine, as will be hereinafter explained. This cone is preferably from 8 to 10 inches 85 in diameter and the angle between its sides which affords the best results is approximately 120°. 3 indicates the stylus or needle which engages the record groove. This needle is rigidly attached to the cone 1 by means of a connecting member indicated, as a 90 whole, by 4 and comprising a central post 5 and two arms 6, 6 extending diametrically opposite each other from the sides of the post. The arms, while being in the same plane with each other occupy an angular position to each other corresponding approximately to the angle between the sides of the cone 1. The extremity of each arm is provided with a foot piece 7 having a threaded orifice to receive a screw 8. The 100

inner end of the post 5 is provided with an axial threaded orifice to receive a screw 9. The connecting member is rigidly attached to the cone in such a position that the needle 5 or axis of the post 5 will be in line with the apex of the cone, in which position the post is secured by means of the screw 9 which passes through a threaded bushing 10 seated at the apex of the cone. The arms 6 extend 10 on each side of the post a considerable distance therefrom and are secured to the wall of the cone by means of the screws 8 before-mentioned, which pass through washers 11 between which and the foot pieces 7 the 15 wall of the cone is clasped. The three connecting points of the members 4 are therefore in line with each other and with the middle point located at the apex of the cone. If desired the arms 6 may extend from the 20 base of the post 5 and along the surface of the cone and be connected thereto by wax along their entire length, thus making an elongated narrow continuous anchorage between the connecting member and the cone 25 which I regard as the equivalent of the three connections arranged in a line. Since the connecting member has no support upon the cone in any transverse or angular direction to its length it is evident that it is more sensitive to movement in that direction than in any direction coincident or parallel to its length. Therefore when the reproducer is mounted to engage the groove in a record 30 it is placed so that the direction of vibrations imparted to the stylus and connecting member by the groove formations shall be transverse to the elongated connecting member. Thus the position of the reproducer in Fig. 1 is adapted for a lateral cut groove 35 or a groove in which the undulations are formed in the side walls of the groove and cause the stylus to vibrate from right to left or side to side. By turning the cone upon its axis through an angle of 90°, the connecting member will be brought into a position 40 transverse to the up and down vibrations caused by the needle running in a record groove of variable or undulating depth formed by the up and down cut. Hence the 45 vibrations in both cases are transverse to the elongated connecting member and the character of the reproduction will be the same in both cases.

In order to shift the reproducer with ease 50 and despatch to either of the two positions stated, I provide a block 12 or a portion of the frame of the instrument with a socket 13 for a post 14 which is adapted for detachable connection with either of two hinges 55 15, 16 fastened to the rim of the cone 90° apart. These hinges are located, one in the same plane with the elongated connecting member and the other in a plane at right angles thereto. When a record is to be reproduced, the pin is screwed into the appro-

priate hinge to conform to the requirements of the "cut" in the record and then inserted in the socket 13; thereafter the cone is allowed to swing downward until the stylus 3 rests upon the record whereupon the reproduction will start. In this inclined position of the cone the needle will be inclined to the face of the record and this inclination will be the same for both styles of record used. When a different style of record is 70 to be reproduced, the pin is removed from the hinge it is in and inserted in the other. The cone is only partially supported by the block or frame, a sufficient portion of its weight being applied through the needle to 75 the record in order to hold the latter steadily in the groove. This weight may be altered by adding weight to or removing it from the rim 2.

The vibrations imparted to the apex of 80 the cone extend to the rim and propagate sound waves in the air which, by reason of the large size of the cone, afford a loud reproduction of the record. I desire to point out that by reason of the direct connection of the 85 needle to the diaphragm and the fact that such connection is elongated, I am able to utilize a diaphragm of large size, because with such construction the entire vibration created by the record groove is imparted to 90 the cone, none being lost by loose pivotal joints which are found in the ordinary reproducing devices.

I claim:

1. A reproducer for phonographic machines consisting of the combination of a diaphragm, a stylus and a connecting member by which the stylus is rigidly attached to the diaphragm, said connecting member being attached to the diaphragm at three 100 points only located in a diametrical plane thereof.

2. A reproducer for phonographic machines consisting of the combination of a diaphragm, a stylus and a connecting member by which the stylus is rigidly attached to the diaphragm, said connecting member being elongated and narrow in shape and being connected to the diaphragm at three 110 points located in a straight diametrical line, the middle point of connection being at the center of the diaphragm and the connecting member being at all other points out of contact with the diaphragm.

3. A reproducer for phonographic machines consisting of the combination of a diaphragm, a stylus and a connecting member by which the stylus is rigidly attached to the diaphragm, said connecting member comprising a central post in which the 120 stylus is held and two arms extending from said post and in opposite directions, the post and the extremities of the arms being attached to the diaphragm.

4. A reproducer for phonographic ma-

chines, consisting of the combination of a diaphragm, a stylus and a connecting member by which the stylus is rigidly attached to the diaphragm, said connecting member being attached to the diaphragm at a plurality of points located in line with each other and being out of contact with the dia-

phragm at all other points, said stylus being located in the same plane as the points of attachment of the connecting member with 10 the diaphragm.

In witness whereof I subscribe my signature.

JOHN H. J. HAINES.
